UNITED STATES PATENT OFFICE.

ANTON MAYER, OF CHICAGO, ILLINOIS.

AIRSHIP.

1,030,826.

Specification of Letters Patent. Patented June 25, 1912.

Application filed December 20, 1911. Serial No. 666,927.

To all whom it may concern:

Be it known that I, ANTON MAYER, a citizen of Bavaria, residing at Chicago, in the county of Cook and State of Illinois, have 5 invented a certain new and useful Improvement in Airships, of which the following is a full, clear, concise, and exact description, reference being had to the accompanying drawings, forming part of this application.

10 My invention relates to the class of airships commonly known as biplanes.

It consists of a novel arrangement of the planes for obtaining increased stability; also of a novel arrangement for simultaneously 15 tilting some of these planes, so as to safeguard the airship against overturning, in case of squalls or of accidents necessitating a sudden descent.

10 My invention is shown in the accompanying drawings forming part of this specification, in which—

Figure 1 is a plan view. Fig. 2 is a side elevation, Fig. 3 is an end elevation, Fig. 4 is an enlarged view of the shaft, cog and chain arrangement for operating the tilting planes. Fig. 5 shows an alternative arrangement of the springs for returning the tilting planes to their normal position. Fig. 30 6 shows an alternative spring arrangement in which the springs are fastened to the tilting members and to the framework of the airship. Fig. 7 is a diagrammatic view showing the steering arrangement. Fig. 8 is a diagrammatic view showing the arrangement of the means for controlling the tilting of the four safety bi-planes pivoted to the sides of the frame. Fig. 9 is a diagrammatic view of the control for the stabilizing planes at the front and rear of the airship. Fig. 10 is a diagrammatic view of the control of the elevating and lowering planes at the front and rear of the airship.

Like reference characters are used to designate 45 like elements in each of the drawings, but in some of the drawings portions of the flexible controlling members and other details have been omitted to avoid confusion.

50 In the drawings, 1 is the framework of an airship, supporting engines 2, 2 and shafts 3, 3, the latter carrying propellers 4, 4.

55 5 is a substantially rectangular plane approximately over the center of the framework.

6, 6' are tandem biplanes pivoted to longitudinal portions 1'. The portions 1' of the framework extend longitudinally of the airship, being substantially parallel and preferably close to the longitudinal sides of the plane 5. There are four pairs of these tandem biplanes, pivoted along their inner edges lengthwise of the airship, their inner edges being substantially in line with the outer edges of the fixed plane 5. These biplanes extend respectively forward and rearward of the fixed plane 5, their inner corners being adjacent to the corners of plane 5. 60

7 is a rope fastened to the upper plane of the tandem biplane 6, this being preferably forked as at 7'. Rope 7 leads over a pulley 8, preferably fastened to an upright post 9, and down along the post 9, 70 over another pulley 10 to one end of a chain 11. The chain 11, which is preferably a so-called link belt chain, passes part way around the cog wheel 12, the links of the chain intermeshing with the teeth of the cog wheel. Cog wheel 12 is fastened rigidly to a shaft 13, which the operator can turn by means of a hand wheel 14. The other end of the chain 11 is fastened to a return rope 15 leading over a pulley 16 to the lower 80 plane 6' of the biplane 6. 85

16 is a link connecting planes 6 and 6' at the points where the ropes 7 and 15 are fastened to the planes. The link 16 in connection with the ropes 7 and 15 and chain 90 11 thus forms an endless flexible member engaging the cog wheel at 12 in one direction and fastened to the biplane 6, so that rotating this cog wheel in one direction will raise the side edges of the biplanes 6 and 95 will thereby tilt the biplane 6 to which the ropes 7 and 15 are fastened. Rotating the cog wheel in the opposite direction will return the biplane 6 to its normal position substantially parallel with the plane of the 100 central plane 5. Each of the biplanes 6 is similarly controlled and the wheel 12 has a separate series of cog wheels, as 12^a, 12^b, 12^c, for each controlling cord 7.

17 and 17^a are stabilizing planes pivoted 105 at the front and rear of the framework on axes crosswise of the latter.

18 is a rope leading upward from the front stabilizing plane 17 over pulleys 19 and 19^a to one end of a chain 20 which intermeshes with a cog 21, this cog wheel being also fastened rigidly to the shaft 13. 110

The other end of the chain 20 is fastened to a rope 21^a leading over a pulley 22 to the under side of the stabilizing plane 17. Similarly a cog wheel 21^b, also fastened to the shaft 13, meshes into a chain 20^a connected at its opposite ends to ropes 21^c and 21^d, leading respectively to the upper and lower sides of the rear stabilizing plane 17^a.

23 and 23^a are elevating and depressing planes pivoted respectively to the front and rear of the framework and connected by upward ropes 24 and 24^a and downward ropes 25 and 25^a to chains 26 and 27 intermeshing with cog wheels 28 and 29 on a shaft 49 passing through the hollow shaft 13 to another hand wheel 30. The planes 23 and 23^a are pivoted on axes extending crosswise of the airship, their axes corresponding substantially with the front and rear edges of the plane 5. 31 and 32 are front and rear rudders pivoted to the framework on vertical axes and connected by ropes 33 and 34 to a steering pedal 35, preferably placed close to the hollow shaft 13, so that the operator can do the steering with his feet.

36, 36 are chains leading from the engines 2, 2 to the propeller shafts 3, 3.

37, 37 are stirrups rigidly fastened to the lower portion of the frame 1, and supporting parallel tubes 38, 38. These tubes have closed ends and are preferably made of aluminum and are filled with air, so as to serve as floats for the airship in case it should descend upon water.

39 and 39^a are legs connecting a wheel 40 with the stirrup and the framework, there being preferably a spring 41 in one of these legs to cushion the effect of having the wheel strike the ground suddenly.

42, 42 are bumpers or stops against which the tilting biplanes will strike when tilted to the extreme advisable angle. These bumpers are preferably made of metal bars secured to the upright posts of the framework, such as the post 9, it being the function of these bumpers to keep the oppositely disposed tilting biplanes from striking against each other in case they are too suddenly tilted from their normal position by the upward pressure of air when the downwardly leading controlling ropes are released.

In operating the device of my invention, the four auxiliary biplanes 6, 6' and the auxiliary stabilizing planes 17 and 17^a are normally in substantially the same plane as the central plane 5, being locked in this position by a latch 43, which normally locks the shaft 13 against rotation and which, therefore, prevents motion of the endless flexible members composed of the chains with the ropes and links fastened to the same. In case of a sudden squall or of an accident (such as exhausting the supply of gasoline while the aviator is high in the air) demanding a rapid descent, the operator releases the

catch 43, thereby allowing the upward air pressure to tilt or rock the four auxiliary side planes 6 and the two end stabilizing planes 17 at a considerable angle with the central plane 5. When thus tilted, these auxiliary side, front and rear planes, together with the central plane, constitute a formation akin to the surface of an inverted umbrella, which formation will not readily be overturned by swaying or by sudden gusts of wind.

When the operator has thus allowed the safety planes to tilt to the angular position and has descended from a region of tricky winds to one in which a safe air current is flowing, he can restore the tilting planes to their normal position by turning the hand wheel 14, so as to rotate the cog 12 in the direction opposite to that in which it turned while the planes were being tilted. Owing to the resistance of the air, this returning of the tilted planes to their normal position might require more than one man's strength. I therefore provide strong springs attached to the shaft 13, tending to keep this in the position in which the tiltable planes are substantially parallel to the central planes 5. For this purpose, I preferably use tension springs 44 fastened at one end by hooks 46 to the framework of the airship and at the other end to a cross-bar 45, which cross-bar is fastened rigidly to the shaft 13 as shown in Fig. 5. Fig. 6 shows an alternative spring arrangement in which springs 48 are fastened at one end to the framework and at the other end to the tilting planes, which springs 48 are extended when the biplanes are tilted and therefore tend to return these planes from their safety positions to their normal positions.

While I have referred to the supporting vanes of the airship as planes, it will be understood by those familiar with the practice of aviation that they are not necessarily plane surfaces, being preferably slightly arched as in Fig. 2, and that in speaking of certain planes as substantially parallel in their normal position, I am referring to the plane which these would occupy if the curvatures were flattened out.

While I have thus shown and described my invention in its preferred embodiment, I do not wish to be limited to the exact form as pictured and described, as obvious modifications could be made in the same without departing from the spirit of my invention.

What I claim as new and desire to cover by Letters Patent is:—

1. In an airship, a propelling mechanism; a framework supporting the same; a substantially rectangular monoplane rigidly secured to the said framework approximately over the center of the same; biplanes fastened to the said framework adjacent to the four corners of the said monoplane, the said

- biplanes being normally parallel to the plane of the said monoplane; manual means by which the operator can tilt the said biplanes and by which he can return the tilted biplanes to a plane parallel to that of the monoplane; and spring mechanism for aiding the operator in returning the tilted biplanes to a plane parallel to that of the monoplane.
- 5 2. An airship including a propelling mechanism; a framework supporting the same, a substantially rectangular monoplane rigidly secured to the framework approximately over the center of the same; tandem 15 biplanes pivoted to the said framework adjacent to the four corners of the said monoplane, the said biplanes being normally substantially parallel to the plane of the said monoplane; and a controlling mechanism 20 for holding the said biplanes in this normal position, the controlling mechanism being adapted to release the biplanes simultaneously, whereby the upward air pressure may tilt the biplanes simultaneously to a safety 25 position.
3. An airship including a propelling mechanism; a framework supporting the same; a substantially rectangular monoplane rigidly secured to the framework approximately over the center of the same; auxiliary planes pivoted to the sides and ends of the framework, the said auxiliary planes being normally held substantially parallel to the plane of the monoplane; a 30 latching mechanism for simultaneously releasing the said pivoted planes, whereby the upward air pressure may simultaneously tilt the pivoted planes to a safety position; and stops for limiting the extent to which the upward air pressure may tilt the pivoted planes when the latch is released; and mechanism actuated by the operator for simultaneously returning the planes to their normal position after they have thus been tilted by the upward air pressure.
- 35 4. An airship including a propelling mechanism; a framework supporting the same; a substantially rectangular monoplane rigidly secured to the framework approximately over the center of the same; auxiliary planes pivoted to the sides and ends of the framework, the said auxiliary 40 planes being normally held substantially parallel to the plane of the monoplane; a latching mechanism for simultaneously releasing the said pivoted planes, whereby the upward air pressure may simultaneously tilt the pivoted planes to a safety position; and stops for limiting the extent to which the upward air pressure may tilt the pivoted planes when the latch is released; mechanism actuated by the operator for simultaneously returning the planes to their normal position after they have thus been tilted by the upward air pressure; and springs for aiding the operator in actuating the said mechanism.
- 45 5. An airship including a propelling mechanism; a framework supporting the same; a substantially rectangular monoplane rigidly secured to the framework approximately over the center of the same; auxiliary planes pivoted to the sides and ends of the framework, the said auxiliary 50 planes being normally held substantially parallel to the plane of the monoplane; a latching mechanism for simultaneously releasing the said pivoted planes, whereby the upward air pressure may simultaneously tilt the pivoted planes to a safety position; and mechanism actuated by the operator for simultaneously returning the planes to their normal position after they have thus been tilted by the upward air pressure; and springs for aiding the operator in actuating the said mechanism.
- 55 6. An airship including a framework substantially rectangular in outline; a plurality of planes pivoted to the sides and ends of the framework; a latch normally holding the pivoted planes parallel to one another; stops for limiting the extent to which the upward air pressure may tilt the pivoted planes when the latch is released; and mechanism actuated by the operator for simultaneously returning the planes to their normal position after they have thus been tilted by the upward air pressure.
- 60 7. An airship including a framework substantially rectangular in outline; a plurality of planes pivoted to the sides and ends of the framework; a latch normally holding the pivoted planes parallel to one another; stops for limiting the extent to which the upward air pressure may tilt the pivoted planes when the latch is released; mechanism actuated by the operator for simultaneously returning the planes to their normal position after they have thus been tilted by the upward air pressure; and springs for aiding the operator in actuating the said mechanism.

ANTON MAYER.
